(57) **CLAIM**

The ornamental design for a water toy as shown and described.

DESCRIPTION

FIG. 1 is a front, top, right perspective view of a water toy, showing my new design;

FIG. 2 is a front, bottom, left perspective view thereof;

FIG. 3 is a front elevation view thereof;

FIG. 4 is a right side elevation view thereof;

FIG. 5 is a rear elevation view thereof; and,

FIG. 6 is a top plan view thereof.

The broken lines in the figures illustrate portions of the water toy that form no part of the claimed design.
